PACKAGED GOLF BALLS

Seymour Robins, New York, N.Y., assignor to Diamond National Corporation, New York, N.Y., a corporation of Delaware

Filed June 28, 1961, Ser. No. 65,753

Term of patent 14 years

(Cl. D58—2)

FIG. 1

FIG. 2

FIG. 3

FIG. 4.

FIG. 1 is an elevational view of packaged golf balls showing my new design;

FIG. 2 is an end elevation thereof;

FIG. 3 is a perspective view thereof; and

FIG. 4 is a view similar to FIG. 1 on an enlarged scale.

The novel design being characterized in that a plurality of tangentially abutting and linearly disposed golf balls have surface dimples, the balls being retained in compact and sealed relation by a substantially transparent or opaque protecting jacket completely enclosing and forming the sealed package with the golf balls; the package including concavo-convex end caps forming with overlapped ends of a tubular sheath annular bands inwardly of opposite ends of the package due to refractive differential of two layers of the material used in the jacket and caps,

as compared with one layer of the material; the jacket material being shrunk in taut relationship and forming a plurality of essentially flat facets or planar portions disposed in overlying relation to the golf ball dimples of the end and intermediate golf balls.

I claim:

The ornamental design for packaged golf balls, as shown and described.
